UNITED STATES PATENT OFFICE.

M. B. GAINES, OF WHEELING, WEST VIRGINIA.

CARRIAGE.

SPECIFICATION forming part of Letters Patent No. 781,512, dated January 31, 1905.

Application filed April 6, 1904. Serial No. 201,809.

To all whom it may concern:

Be it known that I, M. B. GAINES, a citizen of the United States of America, and a resident of Wheeling, county of Ohio, and State of West Virginia, have invented certain new and useful Improvements in Carriages, of which the following is a specification.

My invention relates to new and useful improvements in baby-carriages, and more particularly to a brake for baby-carriages and go-carts; and it consists in the particular construction, arrangement, and combination of parts, which will hereinafter be fully described, and specifically pointed out in the appended claims.

The object of my invention is to provide a brake for baby-carriages and the like which will normally stand "set," or, in other words, will stand in a braking position at all times when the handle is not held in the pusher's grasp, and consequently a baby-carriage which will not have a tendency to run off when released on an incline.

In describing my invention in detail reference is herein had to the accompanying drawings, forming a part of this specification, in which—

Figure 1 is a perspective view of a carriage to which my invention is applied, the body and wheels being shown removed. Fig. 2 is a side elevation of a carriage complete equipped with my invention. Fig. 3 is a top plan view of a portion of the same, the body being removed on the line 3 3, Fig. 2. Fig. 4 is a partial sectional view of a portion of a carriage-frame equipped with my invention. Fig. 5 is a partial sectional view of the centrally-pivoted arm. Fig. 6 is a top plan view of the same, and Fig. 7 is a cross-section of the rubber block.

In said drawings like reference-numerals designate like parts throughout the several views.

Referring to said drawings, 1 indicates the body of a carriage, which is supported above the frame by the ordinary springs 2.

3 indicates the sides of the handle, which are ordinarily bent and extended forward,

forming the sides 4 of the frame, the latter being mounted on the axles 5.

6 indicates the ordinary cross-piece or handle joining the sides 3.

Extending transversely across the frame from one side to the other and supported on the sides 4 thereof is a bar 7, the ends of which are slightly in front of the rear wheels 8 of the carriage. As a means for holding said bar 7 upon the sides 4 keepers 9 are provided, as shown, said keepers being of a length which will permit said bar 7 to be moved forward and backward to and from the said wheels 8. Secured in any suitable manner in the rear face of said bar 7 at the opposite ends thereof is a rubber block 10, which consists of a piece of rubber, leather, or similar material adapted to bear against the tires 11 of the wheels 8 without injuring said tires—that is, without cutting or scratching said tires. Connecting the bar 7 with the rear axle 5 of the carriage are one or more spiral springs 12, which are adapted to normally hold said bar 7 drawn back with the blocks 10 in engagement with the wheels 8.

13 indicates a cross-bar having its ends held in slots 14, provided in the sides 3 slightly in front of the handle 6. Attached to each end of said cross-bar 13 is the end of a cord, wire, or chain 15, the opposite end of which is attached to one end of an arm 16, which is pivoted intermediate its ends upon the front axle 5. Said cord, wire, or chain 15 preferably passes underneath the rear axle 5, in or on which is mounted a friction-reducing wheel 17, which said cord, wire, or chain 15 engages. The sides 3 of the handle are preferably bored out to a point slightly in the rear of the rear axle 5, as shown, so as to inclose the cord 15, and thus remove any unsightliness which might be the result of having said cord outside the said sides 3 of the handle. The portion which comes in contact with the wheel 17 is preferably a chain, as shown, and, as is obvious, this chain may be either a plain link chain or a sprocket-chain. In the latter case,

however, a sprocket-wheel will be used instead of the wheel illustrated.

Attached to the end of the arm 16 opposite that to which is attached the end of the cord, wire, or chain 15 is one end of a wire or rod 18, the opposite end of which is attached to the bar 7.

Now, as is apparent, the rubber blocks 10 are normally held in engagement with the wheels 8 by the springs 12, and to remove said blocks 10 from contact with the said wheels to allow the free movement thereof the operation is substantially as follows: The handle 6 and cross-bar 13 are together grasped with the hands. Then by a slight pressure or closing of the hands the said cross-bar is drawn backward toward said handle 6, the ends of said cross-bar sliding in the longitudinal slots 14. As said cross-bar is drawn back the cords, wires, or chains 15, attached thereto, are also drawn back, turning the arms 16 on their pivots 19, which arms, through the wires or rods 18, attached to their opposite ends, draws the bar 7 forward, releasing the rear wheels 8 from contact with the rubber blocks 10.

From the foregoing it will be seen that the carriage remains normally locked at all times when the handle and cross-bar are not actually held in the grasp of the operator, and consequently that the danger of a carriage running off on an incline when the handles are temporarily released is eliminated.

It will be seen that I have described my invention more or less in detail and that various minor changes may be made in the construction and arrangement of parts without departing from the spirit or scope of the invention—as, for example, the dividing of the handle 6 into halves and allowing one of said halves to serve as a cross-bar 13. Hence I do not wish to limit myself to the precise construction and arrangement of parts herein shown and described.

Having thus described my invention, what I claim as new, and desire to secure by Letters Patent, is—

1. In a baby-carriage, the combination with the axles, side handles and the rear wheels, of

a transverse movable bar mounted in front of said rear wheels, longitudinal keepers for holding said bar in place, rubber blocks carried by said bar; springs for normally holding said bar drawn back with said rubber blocks in engagement with said wheels, two centrally-pivoted arms on the front axle, rods connecting said bar with one end of each of said arms, a movable cross-bar carried by the handles, and means connecting said cross-bar with the opposite ends of said pivoted arms whereby they are caused to turn on their pivots and to withdraw the transverse bar from engagement with the wheels, against the tension of said springs, when said cross-bar is drawn back, substantially as described.

2. A brake for baby-carriages comprising a movable transverse bar mounted in front of the rear wheels of the carriage, means for normally holding said bar in engagement with said wheels, centrally-pivoted arms mounted on the front axle, one end of each of said arms connected with said bar, one end of a wire, rope or chain attached to the opposite end of each of said arms, a slidible cross-bar adjacent the push-handle, the opposite end of said wire, cord or chain attached to said cross-bar, and friction-reducing wheels mounted on the rear axle, substantially as described.

3. In a baby-carriage, the combination with axles and rear wheels, of a transverse movable bar mounted in front of said wheels, springs for normally holding said bar in engagement with said wheels, hollow side handles, a movable cross-bar parallel to and adjacent to the push-handle, pivotally-mounted arms on the front axle, a wire connecting one end of each arm with the transverse bar, and pulley-wheels on the rear axle, substantially as described.

Signed by me in the presence of two subscribing witnesses.

M. B. GAINES.
